UNITED STATES PATENT OFFICE.

JOHN E. WADE, OF BROOKLYN, NEW YORK.

CAR-COUPING.

SPECIFICATION forming part of Letters Patent No. 678,921, dated July 23, 1901.

Application filed March 29, 1899. Renewed December 17, 1900. Serial No. 40,214. (No model.)

To all whom it may concern:

Be it known that I, JOHN E. WADE, a citizen of the United States, residing at Brooklyn, in the county of Kings and State of New York, have invented new and useful Improvements in Car-Couplers, of which the following is a specification.

This invention relates to couplers for railway rolling-stock; and it especially appertains to couplers of the vertical-plane or Janney type, each coupler comprising a draw-head with a swinging knuckle or jaw having means for locking the latter in the closed position, as also means for holding the swinging jaw position.

Briefly, my invention comprises a draw-head of substantially the usual character, a swinging jaw pivoted thereto, a movable lock-piece, and a moving device pivotally arranged with relation to the swinging jaw and holding the latter behind the lock-piece when a pair of couplers are united, the complete lock, however, including as elements in its operative condition the swinging jaw, the moving device forming a part thereof, and the movable lock-piece, and the knuckle of an engaged coupler.

In order that my invention may be fully described and explained in detail, I have annexed hereto a sheet of drawings, in which—

Figure 1 is a top plan view of a pair of couplers interlocked. Fig. 2 is a similar view of a pair of couplers unlocked. Fig. 3 is a horizontal sectional view of a coupler, showing the jaw in the closed position. Fig. 4 is a vertical sectional view of the coupler. Fig. 5 is a vertical detail front elevation of the coupler-head, showing the knuckle in the open position; and Fig. 6 is a detail plan view of the knuckle with its pivotal catch portion.

In said figures, A indicates the ordinary draw-bar of a coupler, and B indicates a coupler-head, this being of the usual Master Car-Builders' type.

C indicates the knuckle or swinging jaw, the same having the coupler-arm c and the locking-arm c'.

A pin D is secured in the bifurcated portion of the coupler-head, as seen, and serves as a pivot for the knuckle C, a free space being provided within the bifurcation to permit

of the vertical movement of the knuckle upon its pivot. At the rear of the pintle a forward incline b is formed in the base of the draw-head, and a coincidently-inclined lug b' is arranged beneath the arm c' to cause said arm and the knuckle C to fall by gravity in turning outwardly, and thereby to remain open under all conditions when unlocked. At the rear of the coupler-head in its throat is formed a space E, bounded by a steep inclined wall e at the point opposite the swinging jaw, and being bounded by a vertical shoulder or shoulders e' at a point adjacent to the limit of rearward movement of the locking-arm. A lock-piece or pawl F is placed within said space E and is shaped and arranged to lie normally against the vertical shoulders e' with an upward rearward play, the base e² of said pawl being coincidently inclined with the inclined surface e, whereby its weight alone causes said pawl to remain normally against the lowermost limit of the incline e, and also by its gravity permitting its vertical face to bear normally against the vertical shoulders e'. As seen, the end of locking-arm c' when closed is intermediate and approximately in the vertical plane of the surface of shoulders e', and a loose piece G, which is pivoted to the arm c', as by pivot c² or by other pivotal arrangement, has a lug or lock-catch or finger f, which extends rearwardly (when the knuckle C is closed) to permit it to engage with the pawl F, and has an opposite finger f', which engages by a flange f² or other means against the face of arm c', being thereby limited in its rearward movement. The pawl F being held against lateral movement by contact with the side walls g g, bounding the space E, serves when the lock-catch f has engaged with one side thereof (a recess g' being provided in one of the side walls g to receive said catch f) and when the finger f' is held against the arm c', as by the engaged knuckle of an opposed coupler, to hold said lock-catch, and consequently the arm c', securely in the closed position.

It will be seen that when the coupler is open the loose piece G has an independent movement upon its pin c² relatively with the locking-arm c', said piece lying, as shown in the drawings, in a horizontal recess formed in said arm c' and being limited in its rear-

ward movement by the flange f^2 and limited in its forward movement by a stop f^4 , which is adapted to engage within a recess f^5 in the arm c' . The exact construction and arrangement of the loose piece G is, however, immaterial so long as it swings upon the arm c' and that one portion thereof locks against the pawl F when the other portion is pressed home by an interlocking coupler-knuckle.

10 As will be readily observed, the mere fact of the presence of a body, as the knuckle of another twin coupler, within the coupling cavity of its mate causes the catch f' of the latter to be held close against its arm c' , where-
15 by the catch f is held rigidly in the engaged position against the side of pawl F and is locked thereby. The said pawl F is during the locking movement of arm c' moved rear-
wardly and upwardly upon its incline e by
20 the contact of the rear beveled portion of catch f in its rearward passage; but imme-
diately said catch f has passed the pawl F the latter falls by its own weight into its nor-
mal seat, and thus imprisons the catch f ,
25 whereby the coupling is effected. To open the coupler, the usual crank at the side of the car is employed, together with connecting-
rod (not shown) and a suitable means of con-
necting said rod with the pawl F. Said con-
30 nection may be made through an aperture, as H, in the top of the coupler-head or it may be made through an aperture in the side of the coupler-head. (Not shown.) In case of the aperture being in the top of the coupler-head
35 the pawl F may have a cap I connected to it to close the aperture H, and thus prevent cinders, &c., from entering thereat. Upon releasing the pawl F from one of a pair of interlocked couplers, the knuckle of that particular coupler,
40 being unlocked, will swing outwardly, down the incline b , to the wide-open position. This action, if the coupling mate were of any other character, would have no effect whatever, upon its component parts; but, in this instance, the
45 very action or fact of the knuckle of one coupler being withdrawn, by unlocking, from another coupler, both being of my construction, causes the catch of the latter to be released from engagement with its pawl by the dual
50 action of the outward gravity fall of the locking-arm and the removal of the actual bulk of the other coupling-knuckle, which permits the fingers ff' to turn upon their pivot. Thus

whereas one main feature of my invention lies in the mere fact of the engagement of a pair of 55 my couplers, causing the independent locking mechanism of each coupler to be opera-
tive, another essential feature is the fact that the unlocking of one of a pair of engaged couplers and its withdrawal from its mate 60 causes the locking members of both couplers to open wide and to remain positively open under all conditions excepting that of being coupled.

Having now described my invention, I de- 65 clare that what I claim is—

1. A coupler comprising a draw-head, a swinging jaw pivoted therein, a lock-catch pivoted to said jaw, a movable locking-piece, and a transient body in the coupler-jaw to 70 render said lock-catch operative.

2. In a coupler comprising a draw-head, a swinging jaw pivoted therein, and a lock-
catch pivoted to said jaw, a locking-pawl, means whereby the continual engagement of 75 a twin coupler therewith causes said catch and pawl to be interlocked; and means where-
by the withdrawal of the twin coupler alone causes said pawl and catch to become auto-
matically disengaged. 80

3. A pair of twin couplers each comprising a draw-head, a swinging jaw and a moving lock-piece; together with means when said couplers are interlocked, whereby the disen-
gagement of the lock-piece of one coupler, to 85 open it automatically, causes the other coupler to open likewise.

4. In a coupler, a draw-head, a swinging jaw therein, coincident inclines upon the draw-head and jaw to raise and lower the lat-
ter as it turns, a catch-finger pivoted to said jaw, a gravity lock-piece, a shoulder to limit the forward movement of said lock-piece, and a rear, inclined bearing to crowd it against 90 said shoulder; together with means as an en-
gaged twin-coupling jaw, to hold the catch-
finger in engagement with the lock-piece when the coupler is closed. 95

In testimony whereof I have hereunto set my hand in the presence of two subscribing 100 witnesses.

JOHN E. WADE.
